UNITED STATES PATENT OFFICE.

LEROY L. Salfisberg, of Newark, New Jersey, assignor to Ivers-Lee Company, of Newark, New Jersey, a corporation of Delaware.

ARTICLE-FEEDING MECHANISM.

Application filed June 5, 1920. Serial No. 386,828.

To all whom it may concern:

Be it known that I, LEROY L. Salfisberg, a citizen of the United States, and a resident of Newark, in the county of Essex and State 5 of New Jersey, have invented an Improvement in Article-Feeding Mechanism, of which the following is a specification.

The present invention relates to an improvement in article feeding mechanism 10 which may conveniently be used in connection with packaging machines, more particularly of the type designed to package articles such as candies, medicinal tablets and the like. One object of the invention 15 is to facilitate and control the distribution of articles as they are withdrawn from a hopper and in such a manner that there will be a reliable and continuous supply of articles presented in position for permanent 20 packaging.

One embodiment of my invention is illustrated in the drawings accompanying the present specification, and in which—

Figure 1 is a top plan view, and 25 Figure 2, a view in vertical section on the line 2—2 of Figure 1.

Referring to the drawings, the articles to be packaged may conveniently be held in a hopper 1 having a laterally constricted discharge passage 2 and a substantially cone shaped bottom portion 3 interposed between the hopper 1 and the discharge passage 2. An article deflecting member 4 is arranged within the container 30 opposite the entrance to the passage 2 and spaced therefrom sufficiently to allow articles to move from the main portion of the container into the constricted portion without, however, having the entire weight of 35 the overlying articles bearing directly upon those which have already found their way into the constricted portion 2. An article carrying platen 5 is arranged opposite the discharge opening of the passage 2 and ex- 40 tends beyond the edges of said opening, said platen being mounted for rotation to impart centrifugal motion to articles which have been moved through the passageway into position on the upper or supporting 45 surface of the platen. This surface is pref- 50 erably enclosed in a housing having a lateral wall 6 and a transverse wall 7, said trans-

verse wall overlying the upper or supporting surface of the platen and spaced therefrom to permit the free movement of articles 55 across said surface in a predetermined relative position. As indicated in Figure 2, the lateral or upright wall 6 of the housing is provided with a threaded portion 8 which engages a similarly threaded portion 9 of 60 the transverse or upper wall 7. Thus, by moving one threaded portion with respect to the other, the distance between the upper or supporting surface of the platen and the interior or lower surface of the wall 7 may 65 be varied to accommodate articles of different sizes. The platen 5 is shown with a hollow interiorly threaded centrally arranged hub 10 adapted to receive the threaded end of a shaft 11 carrying a gear 70 12 which may be driven by any suitable means not shown. A nut 13 threaded on the shaft 11 and engaging a face of the hub 10 may be utilized to fasten the platen securely on the end of the shaft at any de- 75 sired position of vertical adjustment thereon. Thus, by rotating the shaft 11, the platen 5 is rotated and accordingly moves the supported articles away from its center and into position to be intercepted by a 80 take-off chute 14, indicated in dotted lines in Figure 1, said chute being substantially tangential with respect to the platen 5. The inner or open end of said chute thus receives articles as they are forced from the rapidly 85 rotating platen. The opposite end of the chute is closed but the articles are permitted to be discharged therefrom through an opening in the bottom wall of the chute ar- 90 ranged adjacent to the terminal stop 15 thereof, said opening, in the present embodiment of my invention, communicating with a passageway 16 in a gear 17 normally meshing with a toothed portion of the platen 5. A sleeve 18 having a flanged por- 95 tion 19 is mounted in a bearing 20 and is adapted to rotate with the gear 17 when the latter is actuated by the rotation of the platen 5. A flexible conduit 21 may be secured to the lower or discharge end of 100 the sleeve 18 and in position to receive articles as they are forced through said sleeve from the chute 14, said articles being conveyed by said conduit into such position.

that they will be interposed in the path of an article displacing mechanism such for example as a rotatable member 22 having article engaging or displacing arms or pins 23, said arms being arranged to engage and displace in succession articles as they are discharged from the discharge end of the flexible conduit 21. The discharge end of said conduit may conveniently be secured to 10 a sleeve 24 rotatably mounted in a rigid member 25 which also carries an article supporting platform 26 arranged in position to receive articles as they are fed through the discharge opening and to present the same in the path of the rotating pins 23.

To prevent or minimize the clogging or jamming of the articles as they come in contact with the upper or supporting surface 20 of the platen 5, a suitable agitator may be provided, shown in the present case as a rolling member, such as a ballbearing 27, supported on the upper surface of the platen and extending into the discharge opening 25 of the constricted portion 2 of the hopper. In operation, it is contemplated that one or several of these agitators may be set in motion by the rotation of the platen and will serve to expedite the movement of the tablets or other articles toward the supporting 30 surface of the platen.

The device herein described also provides means for conveniently disposing of dust or relatively small particles of the material being packaged. Thus, the upright or lateral wall 6 may be provided with a perforation 28 positioned adjacent to the peripheral edge of the platen 5 so that particles which are thrown from the upper surface of said 40 platen by reason of the centrifugal force operating during rotation thereof will move through said perforation and may be collected in a trough shaped member 29 arranged in particle receiving relation to the 45 opening 28. The peripheral extent of said opening 28 may vary to meet different conditions.

From the foregoing description, it will be clear that the present invention affords a 50 feeding mechanism which is capable of continuous operation at high speed and at a relatively uniform rate. Furthermore, the articles are subjected to a relatively small amount of impact and it is thus possible to 55 utilize the device in the feeding of relatively

fragile tablets or tablets of relatively loose texture without prohibitive breakage.

I claim as my invention:

1. In an article feeding mechanism, the combination of a hopper having a bottom discharge opening, a rotatable article carrying platen in article receiving relation to said opening and extending beyond the edges thereof, a housing enclosing the article supporting surface of the platen, said housing having an opening adjacent to the peripheral edge of the platen to permit the passage of dust and particles of less than predetermined dimension. 60

2. In an article feeding mechanism, the combination of a hopper having a bottom discharge opening, a rotatable article carrying platen in article receiving relation to said opening and extending beyond the edges thereof, a housing enclosing the article supporting surface of the platen, said platen being adjustable with respect to a wall of the housing to accommodate articles of different sizes. 70

3. In an article feeding mechanism, the combination of a hopper having a bottom discharge opening, a rotatable article carrying platen in article receiving relation to said opening and extending beyond the edges thereof, a housing enclosing the article supporting surface of the platen and having a wall spaced from said surface, said wall being movable toward and away from said surface to accommodate articles of different sizes. 80

4. In an article feeding mechanism, the combination of a hopper having a bottom discharge opening, a rotatable article carrying platen in article receiving relation to said opening and extending beyond the edges thereof, and a rolling agitator freely movable on the platen. 90

5. In an article feeding mechanism, the combination of a hopper having a bottom discharge opening, a rotatable article carrying platen in article receiving relation to said opening and extending beyond the edges thereof, and a rolling agitator supported by the platen and extending into the bottom discharge opening of the container. 100

In testimony whereof, I have signed my name to this specification this second day of June, 1920. 105

LEROY L. SALFISBERG.
